CLAIM

The ornamental design for a portable display device as shown and described.

DESCRIPTION

FIG. 1 is a front perspective view of a portable display device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of portion "8" of FIG. 6;

FIG. 9 is a rear perspective view thereof;

FIG. 10 is a partial enlarged view of portion "10" of FIG. 9; and,

FIG. 11 is a partial enlarged view of portion "11" of FIG. 9. The dash-dash broken lines depict portions of the portable display device that form no part of the claimed design. The dot-dash-dot broken line portions of FIGS. 6 and 8-11 are included to show partially enlarged views only and form no part of the claimed design.

1 Claim, 11 Drawing Sheets
